MODULATING OIL BURNER SYSTEM WITH
INTERMITTENT IGNITION

Frederick S. Denison, Minneapolis, Minn., assignor to Minneapolis-Honeywell Regulator Company, Minneapolis, Minn., a corporation of Delaware

Application November 11, 1933, Serial No. 697,687

15 Claims. (Cl. 236—1)

The present invention relates to the automatic control of fuel burning systems and particularly systems for burning fluid fuels such as the now well-known oil burning systems for domestic heating.

One of the broad objects of the present invention is the provision of an automatic control system for fuel burners which system is so arranged that the fuel may be supplied in varying quantities from full flow to zero flow as distinguished from prior art systems in which the fuel is supplied intermittently at maximum flow, together with means for activating an ignition means each time the fuel is turned on after having been turned completely off. Preferably the ignition means is only activated for a short period to establish combustion upon the supplying of fuel after the supply of fuel has been previously terminated, the ignition means thereafter being deactivated and remaining deactivated during the continued supplying of fuel.

In many fuel burning systems of the fluid type, it is difficult to establish combustion unless there is an initial relatively large flow of fuel. A further object of the invention therefore, is the provision of a fuel burning system in which fuel is supplied in varying quantities and so arranged when no fuel is being supplied that upon the resumption of fuel feed a sufficiently large flow will initially be established as to insure proper ignition together with means for activating an ignition means upon such initial supplying of fuel.

Preferably the fuel is supplied in a large or infinite number of stages but it will be readily appreciable that a small number of stages such as two, in addition to the condition of no fuel supply, could be utilized if desired.

Other objects of the invention are the provision of a fuel burning system in which the fuel is supplied in a plurality of stages and the ignition means is activated each time the fuel supply is turned on from zero flow together with the usual safety features including a shutdown until manual intervention if combustion is not established and a recycle of the operations upon a power failure of long or short duration and upon a flame failure after combustion has been successfully established.

Other objects of the invention will become apparent from the following description, accompanying drawings, and appended claims.

For a more complete understanding of the invention reference may be had to the following

description and accompanying drawings, in which:

Fig. 1 is a diagrammatic showing of the preferred form of my improved automatically controlled fuel burning system,

Fig. 2 is a side view, with parts broken away, showing the details of the combustion responsive switching mechanism utilized in the system of Fig. 1,

Fig. 3 is a front view of the combustion responsive switching mechanism of Fig. 2, and

Fig. 4 is a diagrammatic showing of a modified form of my improved automatically controlled fuel burning system.

Referring first to Fig. 1 of the drawings, a fluid fuel burning apparatus is herein illustrated as an oil burning mechanism comprising an oil supply pipe 11 having therein a shut-off valve 12 which is adapted to be opened upon energization of a cooperating electromagnetic winding 9 and closes upon deenergization of electromagnetic winding 9. The oil line 11 also is provided with a proportioning or modulating fuel flow controlling valve 13 which includes a stem 14 that is pivoted to a link 15 as shown at 16. The link 15 is pivoted to a link 17 as indicated at 18. The oil burning mechanism further includes an electrical motor 18 which drives the shaft 19 of a blower 20. The casing of the blower 20 is provided with a pair of arcuate inlet openings 21 through which air enters and is then discharged from the discharge opening 22. The inlet openings 21 cooperate with a shutter 23 which is provided with an operating member 24. Upon rotation of operating member 24, the shutter 23 is adapted to uncover the arcuate inlet openings 21 to vary the amount of air delivered by blower 20 through outlet 22. The link 15 and operating member 24 are positioned in accordance with changes in a condition in a manner which will now be described.

A condition responsive device is herein indicated as a potentiometer room thermostat which comprises a bimetallic element 25 having one of its ends secured and its other end being movable in accordance with changes in the temperature to which the bimetallic element 25 is subjected. The movable end of bimetallic element 25 operates a movable contact member 26 so as to move the same back and forth across a cooperating resistance 27 upon rise and fall in the temperature to which bimetallic element 25 responds. The movable contact member 26 and resistance 27 comprise a control potentiometer.

The control potentiometer is adapted to con-

trol the operation of a solenoid operated switching mechanism comprising a pair of oppositely acting solenoids 28 and 29 which conjointly control the position of a plunger 30. Plunger 30 is connected to a flexible switch arm 31 by means of a rod 32 and a light coiled spring 33. Flexible switch arm 31 carries a pair of contacts 34 and 35 which cooperate with relatively stationary contacts 36 and 37. The solenoid switching mechanism in turn controls a relay comprising a pair of oppositely acting relay coils 38 and 39 which conjointly control the position of a plunger 40. The plunger 40 is connected to a flexible relay switch arm 41 through a rod 42 and a light coiled spring 43. Relay switch arm 41 carries a pair of contacts 44 and 45 which cooperate with relatively stationary contacts 46 and 47.

The relay switching mechanism controls the operation of a motorized controlling means which includes a lower frame plate or base plate 48, an upper frame plate 49 and two side plates 50 and 51. The rotor 52 of an induction motor 53 is mounted upon a rotor shaft 54 that extends through side plate 50 and terminates between side plates 50 and 51. The extended end of rotor shaft 54 carries a pinion 55. In a similar manner, an induction motor, generally indicated at 56, includes a rotor 57 mounted upon a rotor shaft 58 which extends through side plate 51 and terminates between side plates 50 and 51. This extended end of rotor shaft 58 carries a pinion 59. Pinions 55 and 59 mesh with the gears of two gear and pinion assemblies 60 which are mounted upon a shaft 61 that is journaled in side plates 50 and 51. The pinions of gear and pinion assemblies 60 mesh with a pair of gears 62 which are located between side plates 50 and 51 and are secured to a main operating shaft 63 which extends through side plates 50 and 51. A main operating pinion 64 is also secured to main shaft 63 and cooperates with teeth formed in the lower portion of a vertically movable actuating rod 65. Upon rotation of main operating shaft 63 in one direction, the actuating rod 65 is moved upwardly and upon reverse rotation of main operating shaft 63, actuating rod 65 is moved downwardly.

A bracket 66 is secured to the upper side of frame plate 49 and pivotally receives one end of a lever 67 which extends across frame plate 49 and is received within an opening formed in the upper end of actuating rod 65. A roller 68 is mounted within the opening in actuating rod 65 and is adapted to engage lever 67 upon upward movement of actuating rod 65. A stop bracket 69, which is mounted upon the upper surface of frame plate 49, serves to limit the downward movement of the free end of lever 67 and is provided with a stop pin 70 which limits the upward movement of free end of lever 67. The outer free end of lever 67 is connected to actuating link 15 and to the operating member 24 of shutter 23 by a cable means 71.

Main operating shaft 63 is provided with a limit switch actuator 72 which, upon clockwise rotation of operating shaft 63 as viewed from the left, is adapted to engage a switch arm 73 and open a limit switch 74. Main operating shaft 63 also carries a second limit switch actuator 75 which, upon counter-clockwise rotation of main operating shaft 63 as viewed from the left, is adapted to engage a switch arm 76 and open a limit switch 77. Main operating shaft 75 63 also operates a balancing contact finger 78

which sweeps back and forth across a balancing resistance 79 upon reverse rotations of main operating shaft 63.

High or line voltage electrical power is supplied by line wires 80 and 81 and low voltage electrical power is supplied by the secondary 82 of a transformer 83 having a primary 84 which is connected to line wires 80 and 81.

Balancing resistance 79 and control resistance 21 are connected in parallel by means of wires 10 85 and 86. These two resistances are likewise connected in parallel with solenoid windings 28 and 29 (in series) through protective resistances 87 and 88 by means of wires 89, 90, 91 and 92. The outer end of solenoid windings 28 and 29 15 are connected directly across secondary 82 by means of wires 93, 94, 95 and 96. The junction of solenoid windings 28 and 29, movable contact member 26, and balancing contact finger 78 are interconnected by wires 97 and 98. The junction of relay windings 38 and 39 is connected to flexible switch arm 31 through a protective resistance 99 by means of a wire 100 and the outer ends of relay windings 38 and 39 are connected across the secondary 82 by wires 93, 101, 102 and 95. Contact 36 is connected to a small number of turns of solenoid winding 29 by a wire 103 and the contact 37 is similarly connected to a small number of turns of solenoid winding 28 by a wire 104. The remaining circuit connections for the mechanism by which link 15 and operating member 24 are positioned in accordance with changes in the temperature to which bimetallic element 25 responds will be described during the description of the operation of this particular modification of the invention.

Blower motor 18 and electromagnetic coil 9 are controlled by a main switch which is responsive to the same condition to which the control potentiometer responds. In this particular instance, the main switch comprises a pivoted flexible blade 105 to which is secured a second blade 106, the flexible blade 105 being connected to movable contact member 26 by a link 107. Blade 105 cooperates with a relatively stationary contact 108 and blade 106 cooperates with a relatively stationary contact 109. The oil burner control system further includes a relay 110 which comprises a relay coil 111 and a co-operating armature 112 which operates switch 50 arms 113, 114 and 115. Upon energization of relay coil 111 and resulting attraction of armature 112, switch arms 113, 114 and 115 are moved into engagement with contacts 116, 117 and 118. Whenever relay coil 111 is deenergized, the parts 55 return by gravity to the position shown in Fig. 1 of the drawings wherein switch arms 113, 114 and 115 are disengaged from contacts 116, 117 and 118.

The oil burner control system also includes 60 a thermal electric safety switch of usual construction which includes a heating element 119 which, when energized for a predetermined length of time, is adapted to open a switch 120, the switch 120 thereafter remaining open until 65 manually reset. This thermal electric safety switch may well take the form shown in Frederick S. Denison application Ser. No. 226,395 filed October 15, 1927, now Patent No. 1,958,081 issued May 8, 1934. The mixture of oil and air 70 delivered by the fuel burning mechanism 10 is adapted to be ignited by a spark mechanism comprising electrodes 121 and 122 which are connected to the high voltage secondary 123 of a step up ignition transformer 124 having a 75

line voltage primary 125. Line voltage electrical power is supplied to this part of the control system by line wires 126 and 127 and low voltage electrical power is supplied thereto by the 5 secondary 128 of a step down transformer 129 having a line voltage primary 130 that is suitably connected to line wires 126 and 127.

The system also includes a combustion responsive switching mechanism which is shown 10 in detail in Figs. 2 and 3. Referring to Figs. 2 and 3, a casing 131 is provided with a tubular lateral extension 132 that is provided with an opening 133. A collar 134 receives tubular extension 132 and is adapted to cover varying 15 amounts of opening 133, depending upon the position of tubular extension 132. Collar 134 is provided with a flange 135 which may be secured to the stack of a furnace or boiler in a manner well known in the art. A helically 20 coiled bimetallic element 136 has one of its ends secured to tubular extension 132 and its other end is secured to one end of a torsion rod 137 which extends axially through helically coiled bimetallic element 136, tubular extension 132 25 and terminates within case 131.

A collar 138 is secured to torsion rod 137 just inside the case 131. The torsion rod 137 next receives a friction washer 139 and then a switch carrier 140 followed by a coiled spring 141, one 30 end of which bears against switch carrier 140 and the other end of which is received in a spring retainer 142. A similar spring retainer 143 which faces in the opposite direction is next mounted upon torsion rod 137 and is spaced from spring 35 retainer 142 by means of a loosely fitting bushing 144. Spring retainer 143 receives one end of a coiled spring 145 and the other end of this coiled spring abuts a switch carrier 146. Another friction washer 147 is adjacent to the outer face of 40 switch carrier 146 and all of these parts are held in place on torsion rod 137 by a nut 148a which is threaded on the outer extremity of torsion rod 137. In this manner, the switch carriers 140 and 146 are frictionally connected to torsion rod 137 45 and while this frictional connection normally causes switch carriers 140 and 146 to rotate with torsion rod 137 they allow unrestricted movement of torsion rod 137 independently of switch carriers 146 and 147 if the motion of these switch 50 carriers is restrained. A stop pin 148 which is non-adjustably secured to the back of casing 131 lies in the path of movement of both switch carriers 140 and 146 upon counter-clockwise rotation thereof as viewed in Fig. 3. This counter- 55 clockwise rotation is imparted to torsion rod 137 upon a lowering in the temperature to which bimetallic element 136 responds, i. e., the temperature of combustion.

An adjustable stop 149 lies only in the path of 60 movement of switch carrier 140 so as to limit its movement when rotating in a clockwise direction as the result of an increase in the temperature to which bimetallic element 136 responds. A similar stop member which is also adjustable in casing 65 131 is indicated at 150 and lies only in the path of movement of switch carrier 146 and limits its clockwise rotation upon an increase in the temperature to which bimetallic element 136 responds. Switch carrier 146 supports a mercury 70 switch clip 151 which receives a mercury switch 152 that is provided with the usual electrodes 153 and a globule of mercury 154, the arrangement being such that the circuit through mercury switch 152 is opened when switch carrier 146 is 75 in engagement with stop 148. Switch carrier 140

is provided with a pair of mercury switch clips 155 and 156, the former of which is mounted above torsion shaft 137 and the latter of which is mounted below torsion shaft 137. Mercury switch clip 155 carries a mercury switch 157 which is of slightly bent or humped formation as will be seen from an inspection of Fig. 3. This mercury switch 157 is provided with the usual electrodes 158 and a globule of mercury 159, the arrangement being such that the circuit through 10 mercury switch 157 is closed when switch carrier 140 is engaged with stop 148. The lower mercury switch clip 156 supports a mercury switch 160, having electrodes 161 and a globule of mercury 162 and this switch is arranged so as to be in 15 closed circuit position when switch carrier 140 is engaged with stop 148. Mercury switch 157 is the cold switch of the combustion responsive switching mechanism, mercury switch 152 is the hot switch thereof, and mercury switch 160 is the 20 ignition switch.

Upon a decrease in the temperature to which bimetallic element 136 responds, the various parts 25 of the combustion responsive switching mechanism move to the position shown in Figs. 2 and 3 and continued decrease in temperature thereafter is accompanied by continued rotation of torsion shaft 137 but the various mercury switches and switch carriers are restrained from further movement by reason of stop 148. Upon an increase in 30 temperature to which bimetallic element 136 responds both switch carriers 140 and 146 immediately begin clockwise rotation as viewed in Fig. 3. This clockwise rotation of these switch carriers first causes the mercury 154 and 162 in 35 mercury switches 152 and 160 to roll from the left hand ends thereof to the right hand ends thereof whereupon the circuit through mercury switch 152 is closed and the circuit through mercury switch 160 is opened. The mercury 156 40 in mercury switch 157 remains in the left hand end thereof at this time due to the curved or humped formation of mercury switch 157. However, upon further temperature increase and resulting further clockwise rotation of the switch 45 carriers 140 and 146, the mercury 159 in mercury switch 157 rolls over the hump and moves to the right hand end of mercury switch 157 to break the circuit therethrough. Upon further temperature increase, mercury switch carrier 146 engages 50 stop 150 whereupon a further clockwise movement of mercury switch carrier 146 and mercury switch 152 is interrupted. However, further temperature increase results in continued clockwise movement of switch carrier 140 until the same 55 engages its adjustable stop 149. The parts are now in their hot position and it will be noted that the circuit through mercury switch 152 was closed prior to the opening of the circuit through mercury switch 157. Upon a decrease in the temperature to which bimetallic element 136 responds, the switch carriers 140 and 146 will immediately begin to rotate in a counter-clockwise 60 direction. After a relatively small amount of such counter-clockwise rotation the mercury 154 in mercury switch 152 moves to the left hand end thereof to break the circuit through mercury switch 152. A relatively larger movement of switch carrier 140 in a counter-clockwise direction will be necessary to cause the mercury 162 65 in mercury switch 160 to move to the left hand end thereof inasmuch as the stop 149 formerly allowed a larger clockwise rotation of switch carrier 140. The mercury 159 in mercury switch 157 will remain in its right hand end thereof substan- 70 75 75

tially until switch carrier 140 is again moved into engagement with stop 148 by reason of the curved or humped formation of mercury switch 157. It will be noted that during cooling of bimetallic element 136, the circuit through mercury switch 152 is opened relatively quickly but that there is a long delay before the circuit through mercury switch 157 is reclosed. The circuit through mercury switch 160 is closed after opening of the circuit through mercury switch 152 but prior to the closing of the circuit through mercury switch 157. The various devices and elements of which the system of Fig. 1 is composed having now been described, the operation of the complete system will be set forth and the remaining circuit connections which have not previously been mentioned will be specifically traced during the description of the operation.

Operation of the system of Fig. 1

With the parts in the position shown in Fig. 1, the room temperature is at its highest desired point as indicated by the fact that movable contact member 26 is engaging control resistance 27 substantially at the right hand end thereof. At this temperature, blade 105 has just moved from engagement with contact 108. Electromagnetic coil 9 is therefore deenergized as is blower motor 18. Flow controlling valve 13 is closed and the shutter 23 completely covers the inlet openings 21 in blower casing 20. Balancing contact finger 78 is engaging balancing resistance 79 substantially at its left hand end. Solenoid winding 28 is substantially short-circuited by the following circuit: one end of solenoid winding 28, wire 82, protective resistance 88, wire 91, wire 86, balancing contact finger 78, wire 98, and wire 97 to the other end of solenoid winding 28. Similarly solenoid winding 29 is substantially short-circuited by the following circuit: one end of solenoid winding 29, wire 90, protective resistance 87, wire 89, movable contact member 26, bimetallic element 25, and wire 97 to the other end of solenoid winding 29. Solenoid windings 28 and 29 are thus substantially equally energized and plunger 30 is in a central position wherein contacts 34 and 35 are disengaged from contacts 36 and 37. Relay windings 38 and 39 are therefore equally energized so that plunger 40 is in a central position wherein contacts 44 and 45 are disengaged from contacts 46 and 47. Field windings 165 and 167 of motors 53 and 56 respectively are both deenergized and limit switch 77 is open. Inasmuch as no heat is being furnished to the space to be heated, the temperature thereof will soon begin to fall and movable contact member 26 will therefore begin to move along control resistance 27 towards the left end thereof. Such movement of movable contact member 26 will change the current flows through solenoid windings 28 and 29 in such manner that solenoid winding 29 becomes the more highly energized whereby plunger 30 will be moved to the right to bring contact 34 into engagement with contact 36. Such engagement of contact 34 with contact 36 brings protective resistance 98 and a small number of turns of solenoid winding 29 in parallel with relay winding 38 so that relay winding 38 is substantially short circuited whereupon relay winding 38 becomes considerably more highly energized than relay winding 39 and plunger 40 is moved to the right. Movement of plunger 40 to the right brings contact 44 into engagement with contact 46 whereupon an energizing circuit for field winding 165 is established as follows: line

81, wire 168, relay switch arm 41, contact 44, contact 46, wire 169, limit switch 74, wire 170, field winding 165, wire 171, and wire 172 to line 80. Energization of field winding 165 causes motor rotor 52 to rotate in such a direction that main operating shaft 63 is rotated in a clockwise direction as viewed from the left in Fig. 1. It should be noted that the circuit through protective resistance 99 and the small number of turns of solenoid 29 biases plunger 30 additionally to the right to increase the contact pressure between contacts 34 and 36. This clockwise rotation of main operating shaft 63 moves balancing contact finger 78 along balancing resistance 79 towards the right end thereof to again change the respective energizations of solenoid coils 28 and 29 in such manner that they become substantially equally energized whereupon plunger 30 is returned to its central position and contact 34 is separated from contact 36. This separation of contacts 34 and 36 opens the circuit through protective resistance 99 and the small number of turns of solenoid winding 29 which was in parallel with relay winding 38 whereupon relay windings 38 and 39 are again equally energized and plunger 40 returns to its central position, moving contact 44 from engagement with contact 46. The circuit through field windings 165 is thereupon interrupted and motor rotor 52 ceases rotating. This small movement of main operating shaft 63 in a clockwise direction has resulted in a small upward movement of actuating rod 65 whereupon the extreme left end of lever 67 moves upwardly to slightly open oil proportioning valve 13 and to move shutter 23 in such manner as to uncover a small part of inlet openings 21. Each increment of temperature fall in the space to be heated is accompanied by a further movement of movable contact member 26 along control resistance 27 toward the left hand end thereof and the above described action will be repeated so that oil proportioning valve 13 is gradually moved toward its full open position and the shutter 23 gradually uncovers more and more of inlet openings 21 in blower casing 20. During this time however, no oil is fed to the oil burning mechanism inasmuch as electromagnetic coil 9 is deenergized and shut-off valve 12 is therefore closed. When movable contact member 26 reaches the left hand end of control resistance 27, solenoid winding 28 is substantially short-circuited by wire 82, protective resistance 88, wire 91, movable contact member 26, bimetallic element 25 and wire 97. Main operating shaft 63 is then operated until limit switch 74 is opened. At this time, balancing contact finger 78 has been moved to the extreme right hand end of balancing resistance 79 whereby solenoid winding 29 is substantially short-circuited by wire 90, protective resistance 87, wire 89, wire 85, balancing contact finger 78, wire 98 and wire 97. Plunger 40 therefore returns to its central position. At this time oil proportioning valve 13 will be completely opened and shutter 23 will have uncovered enough of inlet openings 21 in blower casing 20 to allow the supplying of the proper amount of air upon energization of blower motor 18 to properly support combustion. Also, at this time, blade 106 just engages contact 108. Such movement of movable contact member 26 preferably corresponds to a temperature drop in the space of substantially 2° F.

Engagement of blade 106 with contact 108 establishes an energizing circuit for relay coil 111, it being remembered that blade 105 has been in

engagement with contact 108 during the greater portion of this space temperature fall. This energizing circuit for relay coil 111 is as follows: secondary 128, wire 173, safety switch 120, wire 174, contact 108, blade 105, blade 106, contact 109, wire 175, wire 176, wire 177, cold switch 157, wire 178, heating element 119, wire 179, wire 180, relay coil 111 and wire 181 to the other side of secondary 128. It will be noted that this initial energizing circuit for relay coil 111 traverses cold switch 157 so that this circuit cannot be completed unless the temperature of combustion to which bimetallic element 136 responds has dropped a predetermined amount depending upon the adjustment of stop 149. Energization of relay coil 111 attracts armature 112 which in turn moves switch arms 113, 114 and 115 into engagement with contacts 116, 117, and 118. Engagement of switch arm 114 with contact 117 establishes a holding circuit for relay coil 111 which is independent of blade 106 and contact 109. This holding circuit is as follows: secondary 128, wire 173, safety switch 120, wire 174, contact 108, blade 105, wire 182, contact 117, switch arm 114, wire 183, wire 176, wire 177, cold switch 157, wire 178, heating element 119, wire 179, wire 180, relay coil 111 and wire 181 to the other side of secondary 128. Engagement of switch arm 113 with contact 116 establishes energizing circuits for blower motor 18, electromagnetic winding 9, and the line voltage primary 125 of ignition transformer 124. The energizing circuit for blower motor 18 is as follows: line 127, wire 184, contact 116, switch arm 113, wire 185, wire 186, wire 187, blower motor 18, and wire 188 to line 126. The energizing circuit for electromagnetic winding 9 is as follows: line 127, wire 184, contact 116, switch arm 113, wire 185, wire 186, wire 188, electromagnetic winding 9 and wire 190 to line 126. The circuit for the line voltage primary 125 of ignition transformer 124 is as follows: line 127, wire 184, contact 116, switch arm 113, wire 185, wire 191, ignition switch 160, wire 192, line voltage primary 125 of transformer 124, and wire 193 to line 126. The high tension secondary 123 of ignition transformer 124 is connected to electrodes 121 and 122 by wires 194 and 195.

Energization of electromagnetic winding 9 opens shut-off valve 12. Inasmuch as oil proportioning valve 13 is in wide open position a full supply of oil will be furnished to the oil burning mechanism. Energization of blower motor 18 operates the blower 20, it being remembered that shutter 23 has been operated to a position wherein the proper amount of air is drawn in through inlet openings 21 and delivered from outlet opening 22 to properly form a combustible mixture with the oil delivered from oil supply line 11. This combustible mixture will be ignited by the spark created by the electrodes 121 and 122 if the system is functioning properly.

If combustion is not established, the combustion responsive switching mechanism remains in the position shown in the drawings with the result that heating element 119 remains energized and, after a predetermined time, safety switch 120 will open rendering the oil burning mechanism completely inoperative by deenergizing relay coil 111. The oil burning mechanism will then remain inoperative until safety switch 120 is manually reset.

Assuming however that combustion is properly established, the temperature of combustion will increase and hot switch 152 will first close as

previously described. Closure of hot switch 152 establishes a maintaining circuit for relay coil 111 which does not traverse heating element 119, cold switch 157, or blade 106 and contact 109. This maintaining circuit for relay coil 111 is as follows: secondary 128, wire 173, safety switch 120, wire 174, contact 108, blade 105, wire 182, contact 117, switch arm 114, wire 183, wire 176, wire 196, hot switch 152, wire 197, switch arm 115, contact 118, wire 198, wire 180, relay coil 111 and wire 181 to the other side of secondary 128. It will be noted that this maintaining circuit shunts the circuit through heating element 119 so as to operatively deenergize the same and render it incapable of supplying further heat to safety switch 120 whereby the safety switch 120 will not be operated to open circuit position to shut down the oil burning mechanism. As the combustion temperature continues to increase, ignition switch 160 will open to deenergize the ignition transformer 124 and thereafter cold switch 157 will open to interrupt both the original energizing circuit for relay coil 111 and the previously described holding circuit therefor. The circuit through heating element 119 is now completely broken.

The oil burning mechanism is now operating at full capacity to supply maximum heat. As a result, the room temperature will begin to rise and movable contact member 26 will start moving along control resistance 27 towards the right hand end thereof. Initial movement of movable contact member 26 in this direction will separate blade 106 from contact 109, thereby interrupting the original energizing circuit for relay coil 111 but the oil burning mechanism remains in operation by reason of the previously described maintaining circuit. This initial movement of movable contact member 26 along control resistance 27 to the right unbalances the energization of solenoid coils 28 and 29 opposite to the manner heretofore described so that solenoid coil 28 becomes the more highly energized and plunger 30 moves to the left thereby bringing contact 35 into engagement with contact 37. Such engagement of contacts 35 and 37 completes a circuit through protective resistance 99 and a small number of turns of solenoid winding 28, this circuit being in parallel with relay winding 38 whereupon relay winding 39 becomes more highly energized than relay winding 38 and plunger 40 moves to the left. This parallel circuit which traverses the small number of turns of solenoid winding 28 pulls plunger 30 more strongly towards the left to increase the contact pressure between contacts 35 and 37. Movement of plunger 40 to the left brings contact 45 into engagement with contact 47 to complete an energizing circuit for field winding 167, it being remembered that limit switch 77 moved to closed position 60 upon initial clockwise rotation of main operating shaft 63 during decrease in the space temperature. This energizing circuit for field winding 167 is as follows: line 81, wire 168, relay switch arm 41, contact 45, contact 47, wire 199, limit switch 77, wire 200, field winding 167, wire 201, and wire 172, to line 80.

Energization of field winding 167 causes rotation of motor rotor 57 in such direction that operating shaft 63 moves in counterclockwise direction as viewed from the left in Fig. 1. Initial counterclockwise rotation of main operating shaft 63 allows limit switch 74 to close and also begins moving balancing contact finger 78 along balancing resistance 79 toward the left end 75

thereof. When balancing contact finger 18 reaches such a point on balancing resistance 19 that the current flows through solenoid coil 28 and 29 are again substantially equalized, the 5 plunger 30 will return to its central position, moving contact 35 from engagement with contact 37. Thereupon, the circuit in parallel with relay winding 38 is opened, whereupon the current flows through relay coils 38 and 39 again 10 become equal and plunger 40 returns to its central position moving contact 45 from engagement with contact 47. In this manner, the circuit for field winding 167 is interrupted and further rotation of main operating shaft 63 15 ceases. This rotation of main operating shaft 63 in counterclockwise direction has slightly lowered actuating rod 65 so that lever 67 moves downwardly and partially closes oil modulating valve 13 and allows less air to flow through inlet openings 21 into the blower 20. In this manner, as the space temperature increases, the supply of oil and air to the oil burning mechanism is decreased. The space temperature may now fluctuate between its desired limits and will be 25 accompanied by a corresponding fluctuation in the amount of heat delivered by the oil burning mechanism. During normal weather conditions, when the weather is not too mild, the room temperature should level off at some point within 30 its desired range so that the oil burning mechanism operates continuously at just sufficient capacity to maintain the space temperature constant or at least within the permissible limit of fluctuation.

35 A decrease in the amount of oil supplied to the burner may result in a slight decrease in the temperature of combustion with the result that switch carrier 146 moves a small amount in a counterclockwise direction as viewed in Fig. 40 3. However, it will be noted that this switch carrier 146 must move considerably from stop 150 before the circuit through hot switch 152 is opened and, by proper adjustment of stop 150, the lowering of the temperature of combustion 45 by reason of a decrease in the amount of oil and air supplied to the oil burning mechanism will not be sufficient to cause hot switch 152 to open and thereby shut down the oil burning mechanism. If the space temperature should continue to rise so that movable contact member 50 is again brought to the extreme right end of control resistance 27 as shown in Fig. 1 of the drawings, the blade 105 will be moved from engagement with contact 108 and the maintaining 55 circuit for relay coil 111 will be interrupted. The oil burning mechanism will therefore be rendered inoperative, electromagnetic coil 9 being deenergized and blower motor 18 also being deenergized. The oil burning mechanism will 60 thereafter only be placed in operation when the room temperature has returned to its lowest desired limit so as to again bring blade 106 into engagement with contact 109 and when the temperature of combustion has dropped sufficiently 65 to cause cold switch 157 to again move to closed circuit position.

If there should be a failure of electrical power at any time while the oil burning mechanism is in operation, the system will immediately shut 70 down and cannot again be placed into operation until the temperature of combustion has lowered sufficiently to close the circuit through cold switch 157 and if, at the time of such power failure, blade 106 is disengaged from contact 109, the oil

burning mechanism will remain out of operation until such time as the cold switch 157 has returned to closed position by lowering of the temperature of combustion and the space temperature has lowered sufficiently to bring blade 106 again into engagement with contact 109. When these conditions are satisfied, the oil burning mechanism control system will recycle and again attempt to establish combustion. Similarly, if there should be a failure of flame during operation of the oil burning mechanism, the system will be rendered inoperative as soon as the temperature of combustion lowers sufficiently to open the circuit through hot switch 152. Again, the system remains inoperative until cold switch 157 recloses and until blade 106 again engages contact 109. At such time, the oil burning mechanism will recycle in an attempt to reestablish combustion.

From the foregoing description of the operation of the system of Fig. 1, it will be seen that the present invention provides a system for burning fluid fuel wherein the demand for heat must be such as to require the delivery of sufficient fuel for initially establishing combustion without difficulty before any fuel whatsoever can be supplied. When this amount of fuel is supplied, ignition means are rendered operative only long enough to ignite the fuel and are thereafter rendered inoperative until the next attempt to establish combustion. Combustion having been established, the flow of fuel is modulated or proportioned in accordance with the demand until some predetermined minimum demand is reached whereupon the fuel burning mechanism is again shut down and cannot be restarted until the above mentioned relatively large demand is again required. While the system of Fig. 1 has been described in connection with the system wherein no fuel is supplied initially until there is a demand for full heat delivery capacity, it will readily be appreciated that it is only necessary for the demand to be such as to supply sufficient fuel for proper ignition. This maximum demand for initially feeding fuel and the minimum demand at which fuel feeding ceases is determined by the making and breaking of blades 105 and 106 with contacts 108 and 109 in respect to the movements of movable member 26 which is herein shown as being controlled by space temperatures. It will also be noted that in the system of Fig. 1, the flow of fuel is controlled by the cooperation of two valves, one of which is a shut-off valve that either permits no fuel flow or permits maximum fuel flow, the other valve being a modulating or proportioning valve which is continuously positioned in accordance with demands for heat but fuel can only flow, even though the proportioning valve is opened, at such times as the shut-off valve is opened. The system of Fig. 1 additionally provides all of the usual safety features such as a shut-down until manual intervention upon a failure of combustion initially to be established and recycling of the controls after a stand-by period upon the occurrence of either a flame failure or a power failure and if combustion is not successfully established upon such recycling of the system, the system is shut down until manual intervention.

Turning now to Fig. 4, a somewhat different manner of obtaining the same functions as are obtained in the system of Fig. 1 is illustrated. Similar parts have been referenced to correspond with the same parts in Fig. 1. In the system of

Fig. 4, the proportioning valve 13 and shutter 23 are again constantly changed in position in accordance with fluctuations in the space temperature through a mechanism which is mechanically the same as the mechanism of Fig. 1 but which is rearranged slightly as to its electric connections. It will be noted that the secondary 82 of transformer 83 is connected to the outer ends of solenoid windings 28 and 29 by wires 210, 211, 212, 213, 214 and 215. Contact 36 is connected to a small electromagnetic winding 216 by a wire 217 and contact 37 is connected to a small electromagnetic winding 218 by a wire 219. Field windings 165 and 167 in the system of Fig. 4 are low voltage and replace the relay windings 38 and 39 of the system of Fig. 1. It will be noted that field windings 165 and 167 are connected in series across secondary 82 by wires 210, 220, 221, 222, 223, 224, 225 and 215. This series circuit includes limit switches 74 and 77. Flexible switch arm 31 is connected by a wire 226 to the junction of wires 222 and 223 and is thereby connected to one end of each of the field windings 165 and 167.

The control system for blower motor 18 and electromagnetic winding 9 of valve 12 in Fig. 4 is controlled by switching mechanism operated by lever 67 rather than by a switching mechanism directly controlled by the movements of thermostatic element 25 as in Fig. 1. Lever 67 supports a clip 227 which carries a mercury switch 228 that may be termed the "holding switch" and likewise supports a clip 229 which carries a bent or curved switch 230 which may be termed a "starting switch". The system of Fig. 4 includes a direct current relay coil 231 which upon energization attracts an armature 232. Armature 232 controls switch arms 233 and 234 which respectively cooperate with contacts 235 and 236. The arrangement is such that upon energization of direct current relay coil 231, the switch arms 233 and 234 move into engagement with contacts 235 and 236 and upon deenergization of this relay coil, the switch arms 233 and 234 move from engagement with contacts 235 and 236 by gravity. A second direct current relay comprises a relay coil 237 which, upon energization, attracts an armature 238 that in turn moves a switch arm 239 into engagement with a contact 241, the switch arm 239 thereafter disengaging a contact 240. Such movement of armature 238 also moves switch arms 242 and 243 from engagement with contacts 244 and 245. An ignition means is indicated at 246.

In the system of Fig. 4, the safety mechanism does not include a combustion temperature responsive device but instead includes means which respond directly to the actual presence or absence of flame. This means includes an electrode 247 which is placed in such manner as to be impinged by the flame produced by the oil burning mechanism and also includes a grid flow tube 248 which is provided with a grid 249, an anode 250, and a cathode 251. Power is supplied to the control system for the oil burning mechanism by a transformer 252 which has a line voltage primary 253 connected to line wires 126 and 127. The transformer 252 is provided with a high voltage secondary 254 which supplies approximately 440 volts. The transformer 252 is also provided with a tapped low voltage secondary comprising portions 255 and 256 which are so connected that their polarities are additive and total about 20 volts, each portion furnishing approximately 10 volts. A copper oxide rectifier indicated grammatically at 257 has current paths 258, 259,

260 and 261. A condenser 262 is utilized for purposes to be hereinafter described.

The remaining circuit connections will be completely described during the detailed description of the operation of the system of Fig. 4.

Operation of the system of Fig. 4

The system of Fig. 4 is shown with the parts in the position they assume when the space temperature is at its upper limit so that the oil burning mechanism is inoperative. As the room temperature falls, movable contact member 26 will begin moving along control resistance 27 towards the left end thereof and thereby unbalance the current flows through solenoid coils 28 and 29 so that solenoid coil 29 becomes the more highly energized whereupon plunger 30 will move to the right and bring contact 34 into engagement with contact 36. Closing of contacts 34 and 36 places the small electromagnetic winding 216 in series with field winding 165 whereupon field winding 165 and small electromagnetic coil 216 are energized as follows: secondary 82, wire 215, wire 225, limit switch 74, wire 224, field winding 165, wire 223, wire 226, flexible switch arm 31, contact 34, contact 36, wire 217, small electromagnetic coil 216, wire 211 and wire 210 to the other side of secondary 28. Energization of small electromagnetic coil 216 increases the pull on plunger 30 to increase the contact pressure between contacts 34 and 36. Energization of field winding 165 causes rotation of rotor 52 in such direction that main operating shaft 63 is rotated in a clockwise direction as viewed from the left in Fig. 4.

Initial clockwise rotation of main operating shaft 63 allows limit switch 77 to close whereupon field winding 167 is placed in parallel with the small electric winding 216. Field winding 165 is thereupon traversed by the full current flow which traverses field winding 167 and small electromagnetic coil 216 so that although rotor 51 tends to rotate main operating shaft 63 in a counter-clockwise direction, the torque exerted by rotor 52 to rotate main operating shaft 63 in a clockwise direction will be the greater and the shaft 63 will rotate in a clockwise direction. Balancing contact finger 78 is thereby moved along balancing resistance 79 toward the right end thereof and will reach a point wherein the energization of solenoid coil 28 has been increased sufficiently in respect to solenoid coil 29 to return plunger 30 to its middle position whereupon contact 34 disengages contact 36. Field windings 165 and 167 are thereby connected in series directly across secondary 82 by the following circuit: secondary 82, wire 215, wire 225, limit switch 74, wire 224, field winding 165, wire 223, wire 222, field winding 167, wire 221, limit switch 77, wire 220, wire 210 to the other side of secondary 82. Field windings 165 and 167 are therefore equally energized with the result that main operating shaft 63 ceases rotating and remains stationary. The rotation of main operating shaft 63 which has just taken place caused pinion 64 to raise actuating rod 65 and lift the extreme left end of lever 67 whereby proportioning oil valve 13 opens slightly, shutter 23 is moved to uncover a small portion of inlet openings 21 in the casing of blower 20, and switches 228 and 230 are moved slightly in closing direction.

As the temperature in the space continues to fall, lever 67 will be raised higher and higher whereby mercury switch 230, the holding switch, will first close and thereafter proportioning oil

valve 13 will be moved to full open position. Simultaneously with movement of proportioning oil valve 13 to full open position, the shutter 23 will be moved to a position uncovering the correct amount of inlet openings 21 and starting switch 228 will be moved to closed position. Also, at this time, or upon further slight movement limit switch 14 will be opened by limit switch actuator 12 so as to prevent further energization of field winding 165. Closure of starting switch 228 establishes an energizing circuit for relay coil 231 and electric heating element 119 of safety switch 120 during one half cycle of the alternating current as follows: secondary 256, secondary 15 255, wire 265, holding switch 230, wire 266, starting switch 228, wire 267, contact 244, switch arm 242, wire 268, wire 269, safety switch 120, wire 270, current path 258 of rectifier 257, wire 271, relay coil 231, wire 272, current path 261 of rectifier 257, wire 273, switch arm 239, contact 240, wire 174, heating element 119 and wire 275 to the other side of secondary 256. During the other half cycle of alternating current supplied by secondaries 255 and 256, the circuit for relay 25 231 and heating element 119 will be as follows: secondary 255, secondary 256, wire 275, heating element 119, wire 274, contact 240, switch arm 239, wire 273, current path 259 of rectifier 257, wire 271, relay coil 231, wire 272, current path 30 260 of rectifier 257, wire 270, safety switch 120, wire 269, wire 268, switch arm 242, contact 244, wire 267, starting switch 228, wire 266, holding switch 230, and wire 265 to the other side of secondary 255. Energization of relay coil 231 moves 35 switch arms 233 and 234 into engagement with contacts 235 and 236.

Engagement of switch arm 234 with contact 236 establishes a holding circuit for relay coil 231 and heating element 119 which is independent of switch arm 242 and contact 244. This holding circuit during one half cycle of alternating current delivered by secondaries 255 and 256 is as follows: secondary 256, secondary 255, wire 265, holding switch 230, wire 276, contact 236, switch arm 234, wire 277, wire 269, safety switch 120, wire 270, current path 258 of rectifier 257, wire 271, relay coil 231, wire 272, current path 261 of rectifier 257, wire 273, switch arm 239, contact 240, wire 274, heating element 119 and wire 275 to the other side of secondary 256. During the other half cycle this holding circuit is as follows: secondary 255, secondary 256, wire 276, heating element 119, wire 274, contact 240, switch arm 239, wire 273, current path 259 of rectifier 257, 45 wire 271, relay coil 231, wire 272, current path 260, rectifier 257, wire 270, safety switch 120, wire 269, wire 277, switch arm 234, contact 236, wire 276, holding switch 230 and wire 265 to the other side of secondary 255.

60 Movement of switch arm 233 into engagement with contact 235 establishes energizing circuits for blower motor 18, electromagnetic winding 9 and ignition means 246. The blower motor circuit is as follows: line 126, wire 278, contact 235, switch arm 233, wire 279, wire 280, blower motor 18, wire 281 and wire 282 to line 127. The energizing circuit for electromagnetic winding 9 is as follows: wire 126, wire 278, contact 235, switch arm 233, wire 279, wire 280, wire 283, electromagnetic coil 9 and wire 284, to line 127. The energizing circuit for ignition means 246 is as follows: line 126, wire 278, contact 235, switch arm 233, wire 279, wire 285, switch arm 243, contact 245, wire 286, ignition means 246, wire 287, and wire 75 282 to line 127.

A full supply of oil is therefore supplied to the oil burner since proportioning oil valve 13 has been moved to full open position by lever 67 and shut-off valve 12 has been opened by energization of electromagnetic coil 9. The proper amount of air is drawn in through inlet openings 21 by reason of operation of blower motor 18 and the ignition means should ignite the mixture thus delivered. If combustion should not take place, heating element 119 remains energized and at 10 the end of a predetermined time period, safety switch 120 opens to deenergize relay 231 and render the system inoperative until manual intervention.

Assuming that combustion is properly established, the flame thus produced impinges upon electrode 247 whereupon a circuit from grid 248 through wire 288, electrode 247, and flame 289 to ground 290 is completed whereby the charge from grid 248 is allowed to dissipate. The grid 15 glow tube thereupon allows current flow from the anode 250 to the cathode 251 and establishes a rectified direct current circuit through relay coil 237 as follows: secondary 254, wire 291, wire 292, relay coil 237, wire 293, anode 250, cathode 251 and wire 294 to the other side of secondary 254. Condenser 262 is connected in parallel with relay 237 by means of wires 295 and 296 and serves to smooth out the half-way rectified current supplied by grid glow tube 248 to relay 30 coil 237.

Energization of relay coil 237 attracts armature 238 whereupon switch arm 243 moves from engagement with contact 246 to deenergize ignition means 246. Switch arm 242 likewise disengages contact 244 so that the original energizing circuit for relay coil 231 is interrupted. Switch arm 239 is moved into engagement with contact 241 and thereafter disengages contact 240. Engagement of switch arm 239 with contact 241 establishes a maintaining circuit for relay coil 231 which only utilizes the secondary 255 and is independent of heating element 119. During half the cycle of alternations, this maintaining circuit for relay coil 231 is as follows: secondary 255, wire 265, holding switch 230, wire 276, contact 238, switch arm 234, wire 269, safety switch 120, wire 270, current path 258 of rectifier 257, wire 271, relay coil 231, wire 272, current path 261 of rectifier 257, wire 273, switch arm 239, contact 240, wire 274, heating element 119 and wire 275 to the other side of secondary 255. During the other half cycle this maintaining circuit for relay coil 231 is as follows: Secondary 255, wire 291, contact 241, switch arm 239, wire 273, conducting path 259 of rectifier 257, wire 271, relay coil 231, wire 272, conducting path 260 of rectifier 257, wire 270, safety switch 120, wire 269, wire 277, switch arm 234, contact 238, wire 276, holding switch 230 and wire 265 to the other side of secondary 255.

The oil burning apparatus is now operating at full capacity and as the result the temperature of the space being heated will slowly begin to rise. As the room temperature rises, movable contact member 26 will start traveling along control resistance 27 from the left hand end thereof toward the right hand end. This action increases the current flow through solenoid winding 28 in respect to the current flow through solenoid winding 29 and plunger 30 moves to the left whereby contact 35 is brought into engagement with contact 37. Engagement of contact 35 with contact 37 establishes a circuit as follows: secondary 82, wire 215, wire 214, small electromagnetic winding 218, wire 219, contact 37, contact 35, switch arm 70 75 216 and wire 217 to line 127. Engagement of contact 35 with contact 37 also energizes the small electromagnetic winding 218, wire 219, contact 37, contact 35, switch arm 216 and wire 217 to line 127.

31, wire 226, wire 222, field winding 167, limit switch 77, wire 220 and wire 210 to the other side of secondary 82. The current flow through small electromagnetic winding 218 increases the left-
 5 ward pull upon plunger 30 whereby contact 35 is held firmly in engagement with contact 37. Energization of field winding 167 causes rotation of rotor in such direction that main operating shaft 63 rotates counterclockwise as viewed from
 10 the left in Fig. 4. Initial counterclockwise rotation of main operating shaft 63 moves limit switch actuator 72 out of engagement with limit switch arm 73 whereupon limit switch 74 closes. Field winding 165 is thereby placed in parallel with
 15 small electromagnetic winding 218 and the current flow through both field winding 165 and small electromagnetic coil 218 now traverses field winding 167. Rotors 52 and 57 will thereupon attempt to rotate main operating shaft 63 in oppo-
 20 site directions but since field winding 167 is more highly energized than field winding 165, the rotor 57 will continue rotating main operating shaft 63 in a counterclockwise direction until balancing contact finger 78 has moved along balancing re-
 25 sistance 79 towards the left end thereof to such position that the current flows through solenoid coils 28 and 29 are again substantially equalized whereupon plunger 30 returns to its mid-position and moves contact 35 from engagement with con-
 30 tact 37. Separation of contacts 35 and 37 breaks the parallel circuit through small electromagnetic winding 218 whereupon field windings 165 and 167 are placed in series across secondary 82 by the circuit previously traced. Rotors 52 and 57 there-
 35 fore just balance each other and further rotation of main operating shaft 63 ceases.

During this counterclockwise rotation of main operating shaft 63 pinion 64 has lowered actuating rod 65 accompanied by a lowering of the extended
 40 left end of lever 67. This downward motion of lever 67 moves proportioning oil valve 13 towards closed position and operates shutter 23 to de-
 crease the effective areas of inlet openings 21. This downward movement also causes starting switch 228 to open but holding switch 230 remains closed because of its humped or curved formation and the amount of heat supplied to the space is correspondingly decreased. Now as the space
 45 temperature fluctuates up and down, the oil and air supply will be gradually varied in accordance with these fluctuations and, under normal weather conditions, the space temperature should level off at some point within its permissible range of variation and be maintained thereat by continuous operation of the oil burning mechanism at a rate which just compensates for the demand for heat.

If, during this operation, the flame should become extinguished, the charge on grid 249 will again build up and stop the flow of current from anode 250 to cathode 251 whereupon relay coil 237 will be deenergized and the formerly de-
 50 scribed holding circuit including heating element 119 will be reestablished and after a predetermined period of heating, the system will be shut down unless combustion is reestablished by reenergizing of ignition means 246. In this particular system, there is no stand-by period and then a subsequent recycle to reestablish combustion. If
 55 there should be a failure of electrical power during operation of the system, the oil burning control mechanism will return to the position shown in Fig. 4 and combustion cannot again be reestablished until starting switch 228 is closed as

the result of a demand for full capacity as previously explained.

If the space temperature should again reach its upper desired limit, the lever 67 will be returned to the position shown in Fig. 4 and at this time the curved or bent holding switch 230 will again be tilted at such an angle that its circuit will open and the system will be shut down.

In this system, it will be noted that operation of the oil burning mechanism is not only dependent upon movement of movable contact member 26 but is also dependent upon proper operation of lever 67 so that shut-off valve 12 cannot be opened unless lever 67 has actually moved to a position in which oil proportioning valve 13 is fully opened and shutter 23 has been operated to allow delivery of the proper amount of combustion supporting air. The starting switch 228 closes when lever 67 has been fully raised and opens immediately upon initial lowering thereof. The bent or curved holding switch 230 closes when the lever 67 has been fully raised and remains closed until the lever 67 returns to its lowermost position. The use of a combustion responsive mechanism which responds to the actual presence or absence of flame rather than combustion temperatures may be particularly desirable in proportioning systems of this type wherein flame may be continuously present but the temperature of combustion may vary considerably by reason of the oil burning apparatus operating at varying capacities. It should again be understood in connection with the system of Fig. 4 that the oil burning apparatus need not necessarily be maintained inoperative until there is a demand for full capacity. It is only necessary that the demand should be such that sufficient oil and air will be supplied so as to permit of proper ignition. Likewise, the arrangement should be such that the holding switch 230 opens whenever the minimum demand reaches a predetermined point which point must necessarily vary with different types of fuel burning apparatus.

While two specific embodiments of the invention have been herein described, it will be apparent to those skilled in the art that many changes could be made therein without departing from the spirit of the invention and I therefore intend to be limited only in the purview of the appended claims.

I claim as my invention:

1. An automatic fuel burning system of the class described, comprising, in combination a burner, fuel feeding means therefor, a fuel supply controlling device, ignition means for igniting the fuel supplied thereby, a main control, and means associated with the main control, fuel supply controlling device and ignition means arranged to operate said fuel supply controlling device to supply fuel at at least two different rates besides no supply and to activate said ignition means each time the rate of fuel supply is changed from no fuel flow to a fuel flow, and means operative to render the system inoperative until manual intervention if combustion is not successfully established upon an initial supplying of fuel.

2. In combination with a burner, a fluid fuel supply line; a shut-off valve and a flow proportioning valve in series therein, a movable member which moves throughout a given range upon predetermined changes in the value of a condition, and means associated with said valves and movable member operative to position said flow proportioning valve in accordance with the position

of said movable member at all times, to open said shut-off valve when the movable member reaches a given point in its range of movement when moving in a flow proportioning valve opening direction 5 and to close the shut-off valve when the movable member reaches a given point, spaced from said first point, when moving in the opposite direction.

3. In combination with a burner, a fluid fuel supply line, a shut-off valve and a flow proportioning valve in series therein, a movable member which is moved throughout a given range upon predetermined changes in the value of a condition, means associated with said valves and movable member operative to position said flow proportioning valve in accordance with the position of said movable member at all times, to open said shut-off valve when the movable member reaches a first point in its path of travel while moving in one direction and to close the same when the movable member reaches a second point in its path of travel while moving in the opposite direction, ignition means, and means associated with said movable member and ignition means operative to 25 activate the ignition means when said shut-off valve is moved to open position.

4. In combination with a burner, a fluid fuel supply line, a shut-off valve and a flow proportioning valve in series therein, a movable member which is moved throughout a given range upon predetermined changes in the value of a condition, means associated with said valves and movable member operative to position said flow proportioning valve in accordance with the position of said movable member at all times and to respectively open and close said shut-off valve at two spaced points in the travel of said movable member, ignition means, means associated with the ignition means and shut-off valve operative to 40 activate said ignition means when said shut-off valve is opened, and means responsive to the successful establishment of combustion operative to deactivate said ignition means.

5. An electrical control system for fuel burning systems comprising, in combination, electrically controlled means for supplying fuel and air to a burner, electrically controlled ignition means for igniting the fuel supplied to the burner, a condition responsive main control, and electrical means 50 actuated thereby for controlling said electrically controlled fuel and air supplying means to vary the supply thereof as the value of said condition fluctuates and for energizing said electrically controlled ignition means each time there is an initial supply of fuel and air.

6. An electrical control system for fuel burning systems comprising, in combination, electrically controlled means for supplying fuel and air to a burner, electrically controlled ignition means for igniting the fuel supplied to the burner, a condition responsive main control, and electrical means actuated thereby for controlling said electrically controlled fuel and air supplying means to vary the supply thereof as the value of said condition fluctuates and for energizing said electrically controlled ignition means each time there is an initial supply of fuel and air, and ignition control means for thereafter terminating energization of the ignition means until the next subsequent initial supplying of fuel and air.

7. In combination, a fluid fuel supply line, a shut-off valve and a flow proportioning valve in series therein; means for controlling the supply of combustion supporting air, a movable member

which is moved throughout a given range upon predetermined changes in the value of a condition, and connections between said movable member, flow proportioning valve, air supply controlling means, and shut-off valve operative to vary the supply of fuel and air in accordance with the varying positions of said movable member, to open said shut-off valve at one position of the movable member and to close the same at another position of the movable member.

8. In combination with a burner, a fuel supply line, a shut-off valve and a flow proportioning valve in series therein, an electrically operated blower, a damper for controlling the output of the blower, a condition responsive member movable between predetermined limits in response to predetermined changes in condition to which it responds, and connections between said member, valves, and damper effectuating simultaneous and proportionate movement of said flow proportioning valve and damper in accordance with the movements of said member, opening of said shut-off valve and energizing the blower at one limit of movement of said member, and closing said shut-off valve and deenergizing the blower when said member is at the other limit of its movement.

9. In combination with a burner, a fuel supply line, an electrical shut-off valve and a flow proportioning valve in series therein, a condition responsive element movable throughout a given range in response to predetermined changes in the condition to which it responds, means controlled thereby operative to position said flow proportioning valve in accordance with the movements of said thermostatic element, a starting switch moved to closed position upon movement of said element to such position that said flow proportioning valve is moved to a predetermined flow position, a holding switch moved to open position when said element is in such position that the flow proportioning valve is moved to a predetermined minimum flow position, and starting and holding circuits controlling the operation of said shut-off valve controlled by said starting and holding switches.

10. In combination with a burner, a fuel supply line, an electrical shut-off valve and a flow proportioning valve in series therein, a thermostatic element subjected to temperature changes and movable between limits in response to predetermined changes in the temperature to which it responds, means controlled thereby operative to position said flow proportioning valve in accordance with the movements of said thermostatic element, ignition means, a starting switch moved to closed position upon movement of said thermostatic element to such position that said flow proportioning valve is moved to its maximum flow position, a holding switch moved to open position when said thermostatic element is in such position that the flow proportioning valve is moved to closed position, starting and holding circuits controlled by said starting and holding switches and operative to open said shut-off valve and to activate the ignition means and means independent of said holding switch operative to terminate operation of said ignition means.

11. In combination with a burner, fuel supply controlling means, a member movable throughout a predetermined range in response to predetermined changes in the value of a condition, connections between the fuel supply controlling means and movable member operative to vary the supply of fuel in accordance with the movements

of the movable member whereby the temperature of combustion will vary, and means responsive to the actual presence of flame and independent of the temperature of combustion operative to dis-
5 continue the supply of fuel upon extinguishment of the flame while fuel is being supplied at any rate.

12. In combination with a burner, a fuel flow proportioning valve and a fuel shut-off valve connected in series, a controlled member connected to the flow proportioning valve, a controller associated with the controlled member and operative to variably position the same upon variations in the demand for fuel, and connections controlled by the control member arranged to quickly and completely open the shut-off valve only when the flow proportioning valve has been moved to a predetermined open position after having been closed and to quickly and completely close the shut-off valve when the flow proportioning valve is moved to a second predetermined flow position which is less than said first flow position.

13. In combination with a burner, a fuel flow proportioning valve and an electrically operated fuel shut-off valve, a controlled member, connections between the controlled member and flow proportioning valve by which the latter is positioned according to the position of the former, a first switching means moved to a new circuit controlling position by the controlled member when the same moves to a first position in which the flow proportioning valve is opened to a predetermined position, a second switching means moved to a new circuit controlling position when the controlled member returns to a second position in which the flow proportioning valve is moved to a second predetermined position, circuit connections controlled by said switching means operative to quickly and completely open the shut-off valve when the controlled member moves to said first position and to quickly and completely close the shut-off valve when the controlled member moves to said second position, reversible motor means in control of said controlled member, a variable resistance means associated with the motor means to determine the extent and direction of movement of the motor means, and a condition responsive controller operative to vary the variable resistance means in response to changes in the condition to which it responds.

14. In combination with a burner, a fuel flow proportioning valve and an electrically operated fuel shut-off valve, a controlled member, connections between the controlled member and flow proportioning valve by which the latter is positioned according to the position of the former, a first switching means moved to a new circuit controlling position by the controlled member when 10 the same moves to a first position in which the flow proportioning valve is opened to a predetermined position, a second switching means moved to a new circuit controlling position when the controlled member returns to a second position in which the flow proportioning valve is moved to a second predetermined position, circuit connections controlled by said switching means operative to open the shut-off valve when the controlled member moves to said first position 15 and to close the shut-off valve when the controlled member moves to said second position, reversible motor means in control of said controlled member, a variable resistance means associated with the motor means to determine the extent 20 and direction of movement of the motor means, and a condition responsive controller operative to vary the variable resistance means in response to changes in the condition to which it responds.

15. In combination with a burner, a fluid fuel supply line, a shut-off valve and a flow proportioning valve in series therein, a movable member which is moved throughout a given range upon predetermined changes in the value of a condition, means associated with said valves and movable member operative to position said flow proportioning valve in accordance with the position of said movable member at all times and to respectively open and close said shut-off valve at two spaced points in the travel of said movable member, ignition means, means associated with the ignition means and shut-off valve operative to activate said ignition means when said shut-off valve is opened, and means to thereafter automatically de-actuate said ignition means.

FREDERICK S. DENISON. 45
